LUMINAIRE

Edmund L. Izzi, North Olmsted, Ohio, assignor to Westinghouse Electric Corporation, East Pittsburgh, Pa., a corporation of Pennsylvania

Filed May 21, 1963, Ser. No. 74,989

Term of patent 14 years

(Cl. D48—31)

Fig.1.

Fig.2.

Fig. 3.

Fig. 4.

FIGURE 1 is a perspective view of the luminaire as seen from below a horizontal plane;

FIG. 2 is a side elevational view with the post support fragmentarily shown;

FIG. 3 is a top plan view thereof; and

FIG. 4 is a bottom view with the post support omitted.

The dominant features of the luminaire design are shown by solid lines.

I claim:

The ornamental design for a luminaire, substantially as shown and described.
